BOTTLE

Jay T. Hellmann, Cincinnati, Ohio

Application March 19, 1934, Serial No. 716,382

1 Claim. (Cl. 221—147)

The invention relates to containers and more especially to bottles for service as ink containers, vinegar cruet, sauce bottles and others used by druggists, or for other purposes where pouring is done often and the user does not wish to be bothered with a bottle stopper.

The primary object of the invention is the provision of a container or bottle of this character, wherein the same carries a separable mouth which can function to hold a determined quantity of liquid which is delivered thereto from the body of the bottle and this separable mouth may be utilized for pouring purposes or as a well for ink fluid, the container or bottle being of novel construction.

Another object of the invention is the provision of a container or bottle of this character, wherein the separable neck is adapted to carry a cap which is removable therefrom at its outer end, while arranged at the inner end portion of this neck is a valve which admits a determined quantity of liquid from the body of the bottle and prevents such liquid from flowing back into the body of the bottle and the liquid within the neck may be utilized with safety to the contents of the body of the bottle, the bottle being readily refilled or emptied and of a construction involving simplicity and durability, it being compact and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claim hereunto appended.

In the accompanying drawing:

Figure 1 is a vertical longitudinal sectional view through a bottle constructed in accordance with the invention.

Figure 2 is a side elevation partly broken away and showing the bottle inverted for the transfer of a determined quantity of its contents from the body of the bottle to the neck or mouth thereof.

Figure 3 is a view similar to Figure 2 showing the bottle returned to normal position and a portion of the contents trapped or held in the neck or mouth of said bottle.

Figure 4 is a view similar to Figure 3 showing a slight modification.

Figure 5 is a perspective view of the valve as employed in the bottle.

Similar reference characters indicate corresponding parts throughout the several views in the drawing.

Referring to the drawing in detail, the bottle comprises a body 10, in this instance shown made from glass although it may be made from any other suitable material, which constitutes a container for liquid 11, as for example, writing ink, the top of the body 10 being formed with an externally threaded nipple 12 so that the said bottle may be filled or emptied therethrough. Engaged with the nipple 12 is a separable neck 13 which constitutes the mouth to the bottle.

The neck 13 is formed at its inner end with an externally threaded collar-like coupling portion 14 for threaded engagement with the nipple 13 on the body 10 of the bottle and in this fashion the neck is separably joined therewith. Interiorly 15 of the neck 13, next to the collar-like portion 14, is an annular shoulder 15 to provide a seat for an expansible cork or packing 16 carried by separably connected male and female parts 17 and 18, respectively, these being separably joined by the 20 companion threads 19 formed on the respective parts. The part 17 is accommodated in the annular shoulder 15 to locate the part 18 within the neck 13 and this part has the dished area 20 with a center opening 21 communicative with the 25 center opening 22 in the part 17 through which communication is had between the body 10 and the neck 13, as will be clearly apparent in Figures 1, 2 and 3 of the drawing.

The part 17, concentrically of its opening 22, 30 is formed with a raised valve seat 23 for engagement with a valve 24, its stem 25 being separably connected with a ball weight 26, the stem being loose in the opening 22 in the part 17, so that when the bottle is in normal upstanding position the valve 24 will become automatically seated under the action of the weight 26 to close communication between the body 10 and the neck 13 and on inverting the bottle from its normal upstanding position the valve 24 will leave its seat 35 and communication will be had between the body and the neck of the bottle. The weight 26, next to the stem 25, is provided with a spacing spider 27 which prevents the ball from closing the opening 22 on the inverting of the bottle, so that the flow of contents of said bottle will not be interrupted, to the neck 13 as this spider 27 avoids the ball 26 seating in the opening 22, as will be apparent.

It will be clear that the cork or packing 16 will frictionally hold the parts 17 and 18 within the neck 13 of the bottle on the expanding of the said cork or packing.

The neck 13 outwardly of the parts 17 and 18 55

will function as a well for ink fluid to assure a ready supply thereof to the user of the bottle.

Carried by the neck 13 is a closure cap 28, it being preferably threaded upon the neck and telescoped thereover so as to seal the outer mouth end of said neck.

The bottle will serve as a pouring bottle as well as an ink well for the dispensing of the contents of said bottle.

10 In Figure 4 of the drawing there is shown a slight modification, wherein the neck 29 has the internal integral partition 30 provided with the center opening 31 for the valve, the latter working identically with the valve 24 and including 15 the stem 32 and ball weight 33, respectively, so that in this construction the parts 17 and 18 and the cork or packing 16 will be entirely dispensed with.

10 The valve is formed with an eye 34 so that when it is desired that the neck 13 be emptied of the liquid therein into the body of the bottle 10, a suitable implement, for example, a hook, can be engaged with the eye 34 to lift the valve from its seat 23, thus permitting the liquid to flow back 25 into the bottle, as will be obvious. Also, it may be found advantageous to fill the bottle body 10 with liquid through the neck 13 and to accom-

plish this the valve 24 would have to be lifted from its seat 23 in the manner as just stated.

What is claimed is:

5 The combination of a cylindrical body having an internally threaded coupling end and an externally threaded opposite end, the coupling end being adapted for separable connection with a bottle neck, a dividing wall formed interiorly of the body at the internally threaded end for providing a liquid chamber throughout the major 10 portion of the length of the body and having an opening through said wall, said wall being provided with a valve seat concentrically of its opening, a pendant weighted valve engaged in said opening and automatically sealing itself upon the seat for the closing of the opening on the bringing of the body from a tilted position to a vertical position with the externally threaded end uppermost and for the filling of said chamber when the body is in tilted position by the traffic 20 of a quantity of liquid through the opening from the neck of a bottle when the body is attached to the latter, and a closure separable from the externally threaded end of said body for access to the said chamber therein.
